UNITED STATES PATENT OFFICE.

LUCILE J. PARTIN, OF LAGRANGE, GEORGIA.

DESIGN FOR A DOLL, STATUETTE, OR ARTICLE OF SIMILAR NATURE.

Application filed May 28, 1923. Serial No. 6,308. Term of patent 3½ years.

To all whom it may concern:

Be it known that I, LUCILE J. PARTIN, a citizen of the United States, residing at Lagrange, in the county of Troup and State of Georgia, have invented a new, original, and ornamental Design for Dolls, Statuettes, or Articles of Similar Nature, of which the following is a specification, reference being had to the accompanying drawing, forming a part thereof.

The drawing shows a perspective view of my new statuette design.

I claim:—

The ornamental design for a doll, statuette, or article of similar nature, as shown.

LUCILE J. PARTIN.
